FORGING MACHINE

Paul H. Nast, Claremont, N. H., assignor to Sullivan Machinery Company, a corporation of Massachusetts

Application April 28, 1934, Serial No. 722,925

19 Claims. (Cl. 76—5)

This invention relates to a forging machine, and more particularly to a forging machine for use in making or reforming cutter bits for cutter chains or coal cutting mining machines, and the like.

An object of this invention is to provide an improved forging machine. Another object is to provide an improved forging machine for making or reforming mining machine cutter bits and the like. A further object is to provide an improved cutter bit forging machine of the impact type. Yet another object is to provide an improved forging machine in which a cutter bit, or generally similar article, is formed by a succession of impact blows. A still further object is to provide an improved cutter bit forging machine having improved bit forming die mechanism and associated gaging means. A further object is to provide an improved die block structure for a forging machine of the above character. A still further object is to provide an improved cutter bit forging machine which is relatively light in weight and simple in structure and which may be readily operated by an unskilled operator. These and other objects will, however, hereinafter more fully appear in the course of the following description and as more particularly pointed out in the appended claims.

In the accompanying drawings there is shown for purposes of illustration one form which the invention may assume in practice.

In these drawings,—

Fig. 1 is a vertical sectional view taken through the illustrative form of the improved forging machine, showing the die and hammer mechanism in forging position.

Fig. 2 is a cross sectional view taken on line 2—2 of Fig. 1.

Fig. 3 is an enlarged vertical sectional view taken on line 3—3 of Fig. 1.

Fig. 4 is a view similar to Fig. 3 showing the parts in released position.

Fig. 5 is a vertical sectional view taken on line 5—5 of Fig. 3.

Fig. 6 is an end elevation of the upper die block.

Fig. 7 is a side elevation of the die block shown in Fig. 6.

Fig. 8 is an end elevation of the lower die mechanism.

Fig. 9 is a side elevation of the die mechanism shown in Fig. 8.

The illustrative embodiment of the invention comprises a pedestal 1 having a base 2 and sup-

porting an impact mechanism generally designated 3 and a gaging mechanism 4.

The pedestal of the machine comprises a frame conveniently formed as a casting and having a top portion 5 and parallel side portions 6, 6, the latter suitably secured to a pair of foot portions 7 forming the pedestal base. The top portion 5 of this frame is provided with a suitably formed recess 8 for the reception of a stationary upper die block 9 held in position with in the recess by a pin 10 and a cooperating clamp 11, which is made of spring steel and bent to a radius so that tightening of bolts 12 will clamp the die block. Cooperating with this stationary die block is a lower movable die block 13 which has vertical rectilinear movement and is guided in a vertical guideway 14 formed between the side frames 6, 6 of the machine frame.

In this illustrative construction the impact mechanism comprises a vertical hammer motor 20 of the pressure fluid actuated percussive type and is guided between the side portions of the frame by its upwardly projecting sleeve portion 16 in an annular guide 17 suitably secured to the side portions of the frame. This motor comprises a cylinder 18 having a bore 19 containing a reciprocable hammer piston 20. This cylinder has upper and lower heads 21 and 22, the former herein preferably formed integral with the sleeve portion 16. The lower head 22 is provided with a bore 23 in which a coiled spring 24 is housed, and this spring at its upper end reacts on the lower head and at its lower end upon a head 25 guided in the bore 23 and formed integral with a rod 26 which is pivotally connected at 27 to one end of a pivoted foot lever 28. This lever is journaled at 29 on a pin carried by the pedestal frame and has a pedal or foot plate 30 at its opposite end by means of which the lever may be depressed. Projecting from the end of the lever 28 to which the rod 26 is pivotally connected is a stop portion 31 limiting the downward movement of the die actuating hammer motor; and on its upper surface the lever is provided with a valve stem engaging portion 32 which engages the plunger 33 of a valve (not shown) in a valve body 34 suitably secured to the pedestal frame; and this stem engaging portion opens the valve on sufficient downward movement of the pedal 30 of the lever, thereby admitting pressure fluid to a flexible connection 35 leading to the valve chest 36 of the die actuating hammer motor; and pressure fluid is adapted to be distributed from this valve chest to the motor cylinder to effect reciprocation of the hammer piston. The

hammer piston of this hammer motor has a striking bar 37 guided in the bore 38 of the sleeve portion 16 of the motor guide, and this striking bar is adapted to transmit hammer blows to the lower forming die block.

The lower die block 13 is retained in its guide by a guide plate 40 secured by bolts 41 to a plate 42, the bolts 12 of the clamp 11 also being secured to this plate 42. The plate 42 is also formed with an opening 43 which receives one end of the holding pin 10. The lower die block 13 rests upon the upper end of the sleeve portion 16 of the hammer motor and is entirely supported and actuated by the hammer motor.

Now referring to the improved die structure, it will be noted that formed in the lower die block 13 is an angularly disposed narrow slot 45 of a width adapted to receive the shank 46 of a cutter bit 47, and formed integral with the upper surface of this die block is a die portion 48 having a forming surface 49 adapted to form the forward cutting surface of the cutter bit. Arranged in a transverse slot 50 in the upper die block 9 is a hardened metal plate 51 forming the die portion for the rearwardly inclined surface 52 of the cutter bit. As illustrated, the upper die block 9 has a depending projection 53 having an inclined plane surface 54 forming an abutment for the rear surface of the bit, and this plane surface forms a reaction surface against which the bit reacts during forging of the cutting portion of the bit. The sides of the cutting portion of the bit are formed by concave surfaces 55 formed on laterally movable die members 56, 56. These die members are mounted on a transverse pin 57 arranged in a bore 58 formed in the lower die block 13 and are guided by horizontal plane surfaces 59 thereon engaging corresponding plane guiding surfaces 40 on the die block. These die members 56 are provided with depending ear-like portions 60 having apertures 61 through which the ends of this pin project. Interposed between the body of the die block 13 and the inner sides of the depending portions 60 of these die members are coiled springs 62, 62 for normally urging the die members into their outermost released position. These die members are also provided with outer inclined surfaces 63 adapted to engage with wedge surfaces 64 formed on the inner sides of depending portions 65 integral with the upper die block 9. The die portion 48 of the lower die block 13 is formed with convex sides 66 shaped to conform with the concave surfaces 55 of the side forming die members 56. As the lower die block 13 is moved upwardly by the hammer motor into the position shown in Fig. 3, the side forming die members 56 are driven inwardly in planes at right angles to the planes of movement of the lower die block toward one another by the wedge surfaces 64 on the upper die block, and as the hammer motor percussively actuates the lower die block 13 the side forming die members 56 are driven inwardly to form the side surfaces of the cutting portion of the cutter bit, the die portions 48 and 51 forming the front cutting surfaces and receding surface respectively of the cutting portion. When the foot plate of the lever 28 is released the hammer motor is first stopped and thereafter the lower die block is moved into its released position shown in Fig. 4, the coil springs 62 moving the side forming die members laterally into their outermost released position shown.

The improved bit gaging means comprises a rack member 67 guided at 68, 68 in a bracket 69 suitably secured to the cylinder 18 of the hammer motor and movable upwardly and downwardly with the hammer motor. This rack member is provided at its upper end with an abutment surface 70 formed to engage the lower surface of the cutter bit shank so that when the cutter bit is in forming position it is supported by this rack member. A guideway 71 is formed in the transverse portion 72 of the guide plate 40 for guiding the upper end of this rack bar. For moving the rack bar axially to adjust the position of the bit engaging surface 70 there are formed thereon rack teeth 73 engaged with the teeth of the gear segment 74 secured to a shaft 75 journaled on the bracket 69. Also secured to this shaft is an operating lever 77, and pivotally mounted on this lever is a lever 78 for operating a latch 79 engageable with a ratchet segment 80 secured to the bracket 69. It will thus be seen that when the lever 77 is swung in one direction or the other the rack bar may be slid either upwardly or downwardly as desired and the latch 79 engaging the teeth of the ratchet segment holds the rack bar in adjusted position.

As a result of this invention, it will be noted that an improved cutter bit forging machine is provided having improved die mechanism whereby the cutting portion of the cutter bit is formed in an improved manner by a hammering action. It will further be noted that the improved forging machine is of a comparatively simple and rugged construction which may be cheaply manufactured and maintained in repair at a minimum of expense. These and other uses and advantages of the improved forging machine will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a cutter bit forging machine, a stationary die member, a cooperating movable die member, said die members having die surfaces for forming the forward cutting surface and receding surface of the cutting portion of a cutter bit, die means carried by one of said die members having die surfaces for forming the side surfaces of a cutter bit, and means for actuating said movable die member and said die means for forming said side surfaces concurrently with said forward cutting surface and said receding surface.

2. In a cutter bit forging machine, a stationary die member, a cooperating movable die member, said die members having die surfaces for forming the forward cutting surface and receding surface of the cutting portion of a cutter bit, and die means carried by said movable die member having die surfaces for forming the side surfaces of the cutting portion of a cutter bit.

3. In a cutter bit forging machine, a die mechanism for forming the cutting portion of a cutter bit comprising a stationary die member, a cooperating movable die member, and cooperating die means carried by said movable die member and movable in planes at right angles to the direction of movement of said movable die.

4. In a cutter bit forging machine, a die mechanism for forming the cutting portion of a cutter bit, a gaging mechanism for the cutter bit co-operating therewith during the forming of the cutting portion, and mechanism for effecting forging of a cutter bit by said die mechanism including means for feeding the same bodily into juxtaposition to the bit and an impact mechanism for actuating said die mechanism when so positioned.

5. In a cutter bit forging machine, a die mechanism for forming the cutting portion of a cutter bit, a gaging mechanism for the cutter bit, and an impact mechanism for actuating said die mechanism and mounted for movement into and out of die actuating position, said gaging mechanism being mounted for movement with an element of said impact mechanism.

6. In a cutter bit forging machine, die mechanism for forming the cutting portion of a cutter bit comprising a stationary die member, a co-operating die member movable toward and from said stationary die member, and laterally movable die elements carried by said movable die member.

7. In a cutter bit forging machine, die mechanism for forming the cutting portion of a cutter bit comprising a stationary die member, a co-operating die member movable toward and from said stationary die member, laterally movable die elements carried by said movable die member, and means for moving said last mentioned die elements laterally with a wedging action upon movement of said movable die member toward said stationary die member.

8. In a cutter bit forging machine, die mechanism for forming the cutting portion of a cutter bit comprising a stationary die member, a co-operating die member movable toward and from said stationary die member, laterally movable die elements carried by said movable die member, and wedge means on said stationary die member and cooperating with said laterally movable die elements for moving the latter laterally upon movement of said movable die member toward said stationary die member.

9. In a cutter bit forging machine, a stationary die member, a cooperating movable die member, said die members having portions for forming the forward cutting surface and receding surface of a cutting portion of a cutter bit, die means carried by said movable die member for forming the side surfaces of a cutting portion of a cutter bit, and means for moving said latter die means into forming engagement with the cutter bit with a wedging action upon movement of said movable die member toward said stationary die member.

10. In a cutter bit forging machine, a stationary die member, a cooperating movable die member, said die members having portions for forming the forward cutting surface and receding surface of the cutting portion of a cutter bit, die means carried by said movable die member for forming the side surfaces of the cutting portion of a cutter bit, and wedge means on said stationary die member and with which said die means is engageable for moving said die means into side forming engagement with the cutter bit upon movement of said movable die member toward said stationary die member.

11. In a cutter bit forging machine, a die mechanism for forming the cutting portion of a cutter bit, a gaging mechanism for the cutter bit, and an impact mechanism for actuating said die

mechanism and mounted for movement into and out of die actuating position, said gaging mechanism being supported on and mounted for movement with an element of said impact mechanism.

12. In a cutter bit forging machine, die mechanism comprising a stationary die member, a co-operating die member movable towards and from said stationary die member, laterally movable die elements carried by said movable die member, stationary wedge means coacting with said laterally movable die elements for moving the latter laterally upon movement of said movable die member towards said stationary die member, to effect a forging action, means for moving said co-operating die member and laterally movable die elements toward said stationary die member, and means for imparting a hammering action thereon to effect the bit forging operation.

13. In a cutter bit forging machine, die mechanism comprising a stationary die member, a co-operating die member movable towards and from said stationary die member, a bit support moving with said movable die member, laterally movable die elements carried by said movable die member, stationary wedge means coacting with said laterally movable die elements for moving the latter laterally upon movement of said movable die member towards said stationary die member, to effect a forging action, means for moving said co-operating die member and laterally movable die elements towards said stationary die member, and means for imparting a hammering action thereon to effect the bit forging operation.

14. In a cutter bit forging machine, die mechanism comprising a stationary die member, a co-operating die member movable towards and from said stationary die member, an adjustable bit support moving with said movable die member, laterally movable die elements carried by said movable die member, stationary wedge means coacting with said laterally movable die elements for moving the latter laterally upon movement of said movable die member towards said stationary die member, to effect a forging action, means for moving said co-operating die member and laterally movable die elements towards said stationary die member, and means for imparting a hammering action thereon to effect the bit forging operation.

15. In a cutter bit forging machine, die mechanism comprising a stationary die member, a co-operating die member movable towards and from said stationary die member, means for supporting the shank end of a bit movable with the movable die member and having a top surface for supporting the bit in oblique position, laterally movable die elements carried by said movable die member, stationary wedge means coacting with said laterally movable die elements for moving the latter laterally upon movement of said movable die member towards said stationary die member, to effect a forging action, means for moving said co-operating die member and laterally movable die elements towards said stationary die member, and means for imparting a hammering action thereon to effect the bit forging operation.

16. In a cutter bit forging machine, a stationary die, a co-operating movable die member movable toward and from said stationary die, lateral die members supported for bodily movement with said co-operating die member towards and from said stationary die, and also, relative to said co-operating movable die member, towards said stationary die, means automatically operative to effect said latter movement as said several die members

move toward said stationary die, and means for initially thrusting said die members toward said die member and thereafter imparting a rapid series of hammer blows to effect cooperation of said die members with said stationary die in forging a bit.

17. In a cutter bit forging machine, die mechanism for forming the cutting portion of a cutter bit comprising a stationary die member, a co-operating die member movable toward and from said stationary die member, laterally movable die elements carried by said movable die member, and a hammer motor for imparting in rapid sequence impact blows to said movable die member and said die elements.

18. In a cutter bit forging machine, die mechanism for forming the cutting portion of a cutter bit comprising a stationary die member, a co-operating die member movable toward and from said stationary die member, laterally movable die elements carried by said movable die member,

means for moving said die elements laterally with a wedging action upon movement of said movable die member towards said stationary die member, and a hammer motor for imparting in rapid sequence impact blows to said movable die member and said die elements.

19. In a cutter bit forging machine, die mechanism for forming the cutting portion of a cutter bit comprising a stationary die member, a co-operating die member movable toward and from said stationary die member, laterally movable die elements carried by said movable die member, wedge means on said stationary die member and cooperating with said laterally movable die elements for moving the latter laterally upon movement of said movable die member towards said stationary die member, and a hammer motor for imparting in rapid sequence impact blows to said movable die member and said die elements.

PAUL H. NAST.

CERTIFICATE OF CORRECTION.

Patent No. 2,066,360.

January 5, 1937.

PAUL H. NAST.

It is hereby certified that error appears in the printed specification of the above numbered patent requiring correction as follows: Page 4, first column, line 1, claim 16, after the word "move" insert together; and that the said Letters Patent should be read with this correction therein that the same may conform to the record of the case in the Patent Office.

Signed and sealed this 16th day of November, A. D. 1937.

Henry Van Arsdale,

(Seal)

Acting Commissioner of Patents.
